[57] CLAIM

The ornamental design for an escutcheon for plumbing fitting, as shown.

DESCRIPTION

FIG. 1 is a top perspective view of an escutcheon for plumbing fitting showing our new design;

FIG. 2 is a top plan view thereof;

FIG. 3 is a bottom plan view thereof;

FIG. 4 is a side elevational view thereof, the other sides being the same as the side shown;

FIG. 5 is a cross-sectional view taken on line 5—5 of FIG. 2;

FIG. 6 is a cross-sectional view taken on line 6—6 of FIG. 2;

FIG. 7 is a top perspective view of a modified form of the escutcheon for plumbing fitting shown in FIG. 1;

FIG. 8 is a top plan view of FIG. 7;

FIG. 9 is a right side elevational view of FIG. 7, the left side being a mirror image of the right side shown;

FIG. 10 is a front elevational view of FIG. 7;

FIG. 11 is a rear elevational view of FIG. 7;

FIG. 12 is a bottom plan view of FIG. 7;

FIG. 13 is a cross-sectional view taken on line 13—13 of FIG. 8; and

FIG. 14 is a cross-sectional view taken on line 14—14 of FIG. 8.
